United States Patent Office.

ARTHUR McCARTER, OF SALEM, OHIO.

Letters Patent No. 104,049, dated June 7, 1870.

IMPROVED MEAT-CHOPPER.

The Schedule referred to in these Letters Patent and making part of the same.

To all whom it may concern:

Be it known that I, ARTHUR McCARTER, of Salem, in the county of Columbiana and in the State of Ohio, have invented certain new and useful Improvements in Meat-Choppers; and do hereby declare that the following is a full, clear, and exact description thereof, reference being had to the accompanying drawing and to the letters of reference marked thereon making a part of this specification.

The nature of my invention consists in the construction and arrangement of a "meat-chopper," as will be hereinafter fully set forth.

In order to enable others skilled in the art to which my invention appertains to make and use the same, I will now proceed to describe its construction and operation, referring to the annexed drawing, in which—

Figure 1 is a longitudinal vertical section, and

Figure 2 is a plan view of my machine.

Figure 3 is an enlarged side view of the mechanism for rotating the meat-block.

A represents a cast-iron bed, of any suitable dimensions, round in form, and supported by legs, B B.

In the center of the bed A is a slot, and on each side thereof is a standard, C, between the upper ends of which is pivoted an arm, D, which passes down through the slot in the bed, and is itself slotted below said bed, as shown in fig. 1.

E is the meat-block, provided on its under side with a recess, in which the bed A fits, the meat-block resting upon said bed, and the standards projecting up through a hole in the center of the block.

The meat-block E is provided with an upward-projecting rim or hopper, G.

A casing, H, placed around and over the standards C C, said casing having in its top an opening large enough for the upper end of the arm D to project and vibrate or oscillate from side to side.

On the upper end of the arm D is placed a head, J, having four arms, I I, extending two and two in opposite directions, as shown in fig. 2.

To the outer ends of the arms I I are attached the knives K K, which have a sharp cutting-edge extending on three sides, namely, the under side and both ends. These knives are attached to the arms I, at a suitable angle, as shown in fig. 1.

The knives K K receive the required oscillating motion in the following manner:

On the under side of the bed A, on one side, is attached a plate, L, having two downward-projecting posts, M, in which a shaft, a, has its bearings.

On the outer end of this shaft is placed a cog-wheel, N, turned by a crank, O.

This cog-wheel gears with a small pinion, b, upon the outer end of a shaft, d, which has its bearings in

the lower ends of the posts M, and is at its inner end provided with a balance-wheel, P.

This balance-wheel is provided with a stud or pin, e, passing through the slotted end of the arm D, thus giving to said arm, with its head and knives, an oscillating motion.

Upon the shaft a is placed a four-pointed cam, f, which raises a pawl, g, pivoted on a shaft, i, in a slot on the plate L.

The cam f does not come in immediate contact with said pawl, but operates upon a friction-roller, h, attached to the side thereof, so that, as soon as said roller has passed one of the points on said cam, a spring, k, can throw it down again.

The upper end of the pawl g operates, when it is raised by the cam f, a ratchet-wheel, m, attached to the side of a cog-wheel, n, on the shaft i, and this cog-wheel gearing with a circular cog-wheel, p, on the under side of the meat-block, and thus the necessary rotating motion is communicated to said block.

The cam f, being four-pointed, does not give the block a continuous motion, but moves it only at the instant when all the knives are raised up from the block, that is, in the middle of the oscillating motion, or just when the motion is half finished.

To the casing H is attached an arm, R, having at its outer end a scraper or plow, S, for the purpose of turning the meat from the side of the hopper or rim G.

Having thus fully described my invention, What I claim as new, and desire to secure by Letters Patent, is—

1. The three-edged knives K K, attached to the arms I I, which project from the head J, placed on the upper end of the oscillating arm D, substantially as herein set forth.

2. The arrangement of the bed A, standards C C, meat-block E, and hopper G, substantially as shown and described.

3. The arrangement of the slotted arm D, stud e, balance-wheel P, shafts a d, pinion b, cog-wheel N, and crank O, all substantially as and for the purposes herein set forth.

4. The arrangement of the shaft i, cog-wheel n, ratchet-wheel m, pawl g, roller h, spring k, and cam f, all as described, for giving the meat-block an intermittent rotary motion, substantially as herein set forth.

In testimony that I claim the foregoing, I have hereunto set my hand this 23d day of March, 1870.

ARTHUR McCARTER.
